OPENING GRILL

Ben Cones, 5130 Pleasant Run, Parkway, North Drive,
Indianapolis 19, Ind.

Filed Aug. 24, 1959, Ser. No. 835,734

1 Claim. (Cl. 160—378)

This invention relates to a grill for placement over openings, such for example, as in heating systems where there is a cold or warm air duct having an opening into a room, and it is desired to put a protective shield over that opening and still allow the air to travel therethrough.

In school rooms, particularly, damage is often found to ordinary louver grills which are made out of stamped metal in that the children will throw objects at the grill and bend the louvers causing not only an unsightly appearance, but also a partial closure over the opening in that zone of impact.

A primary object of this invention is to provide a grill which has flexible guard members thereacross and which will not be bent out of shape by impact of articles thrown thereagainst.

A further primary object of the invention is a provision of a most sightly grill together with a low cost of production.

These and many other objects and advantages of the invention will become apparent to those versed in the art in the following description of one particular form of the invention which is made in reference to the accompanying drawings, in which

Fig. 1 is a view in front elevation of a grill embodying the invention;

Fig. 2 is a view in end elevation and partial section; and

Fig. 3 is a view in rear elevation and partial section.

The grill generally designated by the numeral 10 having a shape conforming to the opening over which the grill is to be mounted. In the form herein shown, the frame 11 is rectangular in shape for a rectangular opening. The frame 11 has a front face 12 from which extends rearwardly a flange 13 entirely around the frame, spaced inwardly from the edge 20 of the frame so that the frame portion 12 may overlap the margin of the opening all in the usual and well known manner.

A length of cable, flexible in nature and generally designated by the numeral 14 is threaded back and forth through openings in the flange 13, starting from one end portion 15 lying along the outer side of a flange 13 on one side and carried through the holes 21 formed in the flange 13 on opposite runs thereof. For example, from the length 15 outside of the flange 13, the cable continues by a run 14a from the flange side 13a across the opening to the other flange side 13b, through a hole therein to have this run 14a parallel to the end portion of the flange 13c; thence by a loop 14b on the

2

outside of the flange portion 13b and thence back across the opening by the run 14c through a hole in the flange portion 13a, the run 14c being parallel to the run 14a and this threading is continued entirely across the grill 5 to have the opposite cable end portion 16 carried from the last hole 21 in the flange portion 13a down along the side thereof. The end portions 15 and 16 engaged with the hook ends 17 and 18 of a turnbuckle 19.

Thus by operation of the turnbuckle 19, the cable may 10 be pulled into a taut condition to have the runs all pulled up tightly so as to be without sag, and to be in parallel alignment as indicated in Figs. 1 and 3. Preferably the margins of the holes 16 are rounded somewhat so that the cable will slip therethrough easily as the turnbuckle 19 is adjusted to increase the tautness of the cable. In small size grills, particularly, one single length of a cable may be employed as shown in the drawings, and the diameter of the cable or gauge thereof may be made in accordance with the size of the grill opening, smaller 20 diameters being employed in smaller grills.

As above indicated, the cable offers a flexible resistance to any articles striking the cable, and this is particularly good in gymnasiums, where basketballs and the like may strike the grill. The flexible cable or wire 25 will return to its normal straight line extent across the grill after such impact, and if it does not, then the turnbuckle 19 may be adjusted to again tighten the cable to bring the various runs into straight lines.

Therefore it is to be seen that I have produced a 30 unique, but most servicable grill in a very simple form. While I have shown and described the grill in the one particular form, it is obvious that structural variations may be employed without departing from the spirit of the invention, and I therefore do not desire to be limited 35 to that precise form beyond the limitations which may be imposed by the following claim.

I claim:

A protective grill comprising a rigid unitary frame 40 having a border face with an opening therethrough, and a flange extending rearwardly from and around the margin of said opening, said flange having a plurality of holes therethrough in two opposing sides thereof; a flexible cable threaded back and forth through said openings starting from one cable end portion through the first hole in one side across the grill opening through the first hole in the other flange side, along the outer side of said other side to and through the second hole therein, across the grill opening to and through the second hole in said one side, thence along the outside of the one side and through the second hole in said one side and back and forth through the other holes in the two sides to emerge finally from the last hole in said one side by the other cable end portion; said two portions extending along the outer side of said one side; and a turnbuckle interconnecting said two cable ends for pulling on those ends to tighten the entire cable length.
